UNITED STATES PATENT OFFICE.

JOHN J. HEYS, OF LYNN, MASSACHUSETTS, ASSIGNOR TO UNITED SHOE MACHINERY COMPANY, OF PATERSON, NEW JERSEY, A CORPORATION OF NEW JERSEY.

DESIGN FOR A DIE.

45,115.

Specification for Design.

Patented Jan. 6, 1914.

Application filed March 18, 1912. Serial No. 684,625. Term of patent 14 years.

To all whom it may concern:

Be it known that I, JOHN J. HEYS, a citizen of the United States, residing at Lynn, in the county of Essex and State of Massachusetts, have invented a new, original, and ornamental Design for Dies, of which the following is a specification, reference being had to the accompanying drawing, forming part thereof.

Figure 1 is a plan view of a die showing my new design, and Fig. 2 is a view of the die in side elevation.

I claim:

The ornamental design for a die, as shown.
JOHN J. HEYS.
